Emil Kessler Inventor
By his Attorney
Frank J. Bent

UNITED STATES PATENT OFFICE.

EMIL KESSLER, OF BROOKLYN, NEW YORK, ASSIGNOR TO NONPAREIL TOY & NOVELTY CO., INC., OF NEWARK, NEW JERSEY.

TOY.

1,317,505.

Specification of Letters Patent. Patented Sept. 30, 1919.

Application filed October 31, 1917. Serial No. 199,409.

To all whom it may concern:

Be it known that I, EMIL KESSLER, a citizen of the United States, residing at Brooklyn, in the county of Kings and State of New York, have invented certain new and useful Improvements in Toys, of which the following is a specification.

This invention relates to mechanical toys and aims to provide a simple and inexpensive form of toy which will simulate more or less realistically the antics of a dancing figure.

Briefly, the invention comprises a base in which there is mounted a vertically movable slide projecting up through the top of the base and supporting a figure in position to simulate dancing upon the top of the base, said slide being reciprocated by a star-shaped cam wheel journaled in the base.

Other features will appear as the specification proceeds and will be made clear from a consideration of the accompanying drawing which depicts the invention embodied in a practical form, wherein Figure 1 is a front view of the toy with the base broken away and shown in section; Fig. 2 is a side view taken on a plane at right angles to that of Fig. 1, with the base similarly broken away and shown in section; Fig. 3 is a detached perspective view of the body portion of the slide; and Fig. 4 is a plan of the blank from which such body portion is made.

The base of the toy may be made from sheet metal, with a circular side wall 5, a top 6, a bottom 7 and an outstanding base flange 8, supporting the bottom above the table or support on which the toy is rested.

Reciprocatingly mounted in the base is a vertical figure supporting slide, comprising a sheet metal plate 9, having a dependent lug 10, sliding through a guide slot 11, in the bottom and a stem portion 12, projecting up through a guide opening 13 in the top, this stem being shown as folded or rolled over to form a socket 14 for the rod 15 which directly supports the figure.

The figure element is shown made up of a body portion 16, hung loosely on a hook 17 on the upper end of the rod and provided with jointed leg members 18, the parts being preferably so proportioned that the limbs may just touch the top, as in dancing.

The slide is operated by a cam 19, journaled in the base, as by being mounted on a

shaft 20 pivoted in the side wall of the base, 55 said cam having radiating arms 21, in the nature of a star wheel to engage with an outstanding lug or tappet 22 on the side of the slide plate. This tappet lug is shown formed by blanking out a rectangular tongue 23 60 and then bending this tongue forwardly on the line of its attachment with the plate until it stands at a right angle to the plane of the plate and striking up reinforcing flanges 24 at the edges of the lug which bear against 65 the face of the plate at 25. The lower portion of the plate may be slotted at 26 for the passage of the cam arms therethrough, which slot may be tapered to a narrow guiding throat 27 at its upper end for centering the cams and insuring their proper engagement with the tappet.

The shaft is rotated by means of a crank or handle 28 on its outer end, rotation being thereby imparted to the cam, the radiating 75 arms of which alternately lift and drop the figure supporting slide, causing the figure to "dance" on the top of the base. The antics of the figure can be varied by varying the speed and regularity of rotation. It will be 80 noted that the cam arms have a "wiping" engagement with the tappet, causing said arms to exert their lifting effect more or less gradually, which produces a more grotesque effect and gives a further degree of control 85 for producing different effects.

I claim:

1. A figure toy comprising a base, a figure support consisting of a slide and a detachable rod reciprocatingly mounted in said 90 base, a cam wheel journaled in the base and arranged to operate said support and a figure carried by the support.

2. A figure toy comprising a base, a vertically movable slide mounted in the base 95 and having a post extension projecting up through the top of the base, a rod on the extension, a dancing figure loosely hung on the rod on said post extension, and a cam wheel journaled in the base and engaging 100 the slide for operating the same.

3. A figure toy comprising a hollow base having top and bottom walls provided with guide openings therein, a vertical slide guided in said openings, a rod on the slide, 105 a figure supported on the rod carried by said slide, and a cam wheel journaled in the base and engaging the figure supporting slide.

4. A figure toy comprising a hollow base having top and bottom walls provided with guide openings therein, a vertical slide guided in said openings, an upstanding rod 5 carried by the slide and provided with a hook on its upper end, a figure loosely hung on said hook and having jointed limbs for engaging the top of the base, and a cam wheel journaled in the base and engaging 10 the slide.

5. A figure toy comprising a base, a cam wheel journaled in the base, a sheet metal slide guided in the base having a tongue partially severed therefrom, bent out at an 15 angle thereto and flanged at its edges to form a tappet for engagement by the cam wheel, and a figure supported by said slide.

6. A figure toy comprising a base, a cam wheel journaled in the base, a sheet metal 20 slide guided in the base having a tongue partially severed therefrom, having a tappet for engagement by said cam wheel, and an opening below said tappet tapered to form a guiding throat for the cam wheel, and a 25 figure supported by said slide.

7. A figure toy comprising a hollow base having top and bottom walls provided with guide openings therein, a slide guided in 30 said openings, a figure supported on the slide, said slide provided with a slot, and

means operable within the slot for reciprocating the slide.

8. A figure toy comprising a hollow base having top and bottom walls provided with 35 guide openings therein, a slide guided in said openings, a socketed extension on the slide, a figure supported on said extension and means for operating the slide.

9. A figure toy comprising a hollow base having top and bottom walls provided with 40 guide openings therein, a slide guided in said openings, a figure supported on said slide, a slot in the slide, a flange adjacent the slot and means within the slot engageable with the flange for operating the slide. 45

10. A figure top comprising a hollow base having top and bottom walls provided with guide openings therein, a slide guided in said openings, said slide consisting of a plate having an extension at one end bent upon itself to form a toy supporting, an intermediate blanked out tongue portion bent at an angle to the plane of the plate and a slotted portion at the other end communicating with the intermediate portion and 50 means within the intermediate and slotted portion engageable with the blanked out portion for operating the slide. 55

In testimony whereof I affix my signature.
EMIL KESSLER.
